UNITED STATES PATENT OFFICE.

WILLIAM M. LAMBERT, OF NEW YORK, N. Y., ASSIGNOR TO ANTHONY EISLER & CO., OF NEW YORK, N. Y., A FIRM COMPOSED OF ANTHONY EISLER, JUNIUS NAGEL, AND SAID WILLIAM M. LAMBERT.

ADDRESS LABEL AND CARD.

1,181,098.

Specification of Letters Patent. Patented Apr. 25, 1916.

Application filed September 8, 1915. Serial No. 49,453.

To all whom it may concern:

Be it known that I, WILLIAM M. LAMBERT, a citizen of the United States, and a resident of the borough of Manhattan, city, county, and State of New York, have invented a new and useful Improvement in Address Labels and Cards, of which the following is a specification.

The invention is adapted to a great variety of uses. As an example, in commercial transactions involving the delivery of merchandise by express, freight, parcel post, hand, or otherwise, it is a convenience, both to the vendor and the vendee, to have the bill, invoice or other record accompany the goods, so that upon opening the package, the goods contained therein may be forthwith checked up upon the bill, invoice or other record, and thus assurances to both parties be accurately and speedily had. Also in stock rooms, repair departments, storage places, and the like, it is frequently convenient to have means for inclosing and protecting a memorandum, statement, or other record of the contents of the package, or the ownership, destination, use, or work to be done, attached to the outside of the package. These results have heretofore been secured by the use of the so-called tag envelop, which is an envelop or receptacle adapted to contain the invoice, bill, or other record, made of strong material and usually provided with a reinforced eyelet or eyelets, through which the cord which ties up the package can be passed, or by means of which a supplemental cord can be used to attach it to the package. These tag envelops are, however, objectionable for the following reasons: Where no cord is used to tie up the package, there is nothing to which to attach the envelop and other means have to be provided therefor. This difficulty arises whenever the package is a wooden, fiber or corrugated paper box, the latter being sealed by adhesive material. Also it frequently happens in the handling of such packages that the tag envelop rests upon the floor of the car, wagon, or the like, in which it is being transported, and that another package is placed in such close proximity thereto as to rest upon the tag envelop, so

that when the package is lifted with more or less force for removal from the car, wagon, or the like, that the tag will be either torn off or mutilated, owing to the cutting action of the cord upon the envelop or its equivalent, resulting in loss of the bill or invoice. Furthermore, in handling packages of comparatively little weight, the tag envelop affords a convenient means whereby the delivery people can take hold of the package, so that it is sometimes torn off, or if not, is invariably crumpled, if not mutilated, resulting in corresponding defacement of the bill, invoice, or other matter contained therein.

Under my invention I obviate all of the above stated objections and also secure additional advantages and at a cost materially less than that incident to the use of the tag envelop.

Referring to the drawings, Figure 1 is a plan view of an address label or card embodying my invention; Fig. 2 is a side or edgewise view of the construction shown in Fig. 1; Fig. 3 is a side or edgewise view of an alternative construction; Fig. 4 is a side or edgewise view of a simpler alternative construction; Fig. 5 is a plan view, from beneath, of the construction shown in Fig. 4, the parts being laid out flat; Fig. 6 is a plan view of a construction adapted to use on parcel post packages, so that it may be opened for inspection by the postal authorities; Fig. 7 is a longitudinal sectional view of the construction shown in Fig. 6; Fig. 8 is a plan view of a form of the invention in which the address label or card is made of substantial, strong material, which has been indented, perforated, or scored, so that the part of the label or card superposed upon the envelop or container may be more easily removed; Fig. 9 is a longitudinal sectional view of the construction shown in Fig. 8.

In the side or edgewise views above described, I have shown the two sides of the envelop as quite decidedly separated from each other for the sake of clearness in illustration.

In the drawings 1 represents an address label or card of suitable material, preferably fair quality paper or cardboard, which

may bear the usual or desired advertising matter, and the address words "For" and "From" upon its face. Its back may be entirely covered with any preferred adhesive material 2, or its edges only may be so gummed or provided with adhesive material.

3 (see Fig. 2) is an envelop of any preferred and suitable construction attached as at 4 to the under side of the label or card 1, and may be attached at other points if desired.

5 is the flap of the envelop, which may be supplied with adhesive material 6 upon its edge, as usual, and which projects upwardly 15 through a slit 7 made in the address label or card 1.

The operation of the parts as thus far described is as follows: In the delivery of goods, for instance, a merchant sending a package makes out the bill, invoice or other record therefor, and also writes or prints the name, address and other desired matter upon the label, and upon tipping the flap 5 of the envelop over to the right (see Fig. 2) 20 introduces the bill, invoice, or other record or matter into the envelop through the slit 7. Thereupon the flap 7 is tilted over to the left in the direction of the arrow as shown in Fig. 2, and the adhesive material 6 on the flap being moistened, it is stuck down upon the face of the label, as shown in Fig. 1. The label, the card, or the flap of the envelop may beneficially bear upon their exposed surfaces words indicating that the bill, invoice or other matter is within the envelop beneath the label. The exposed edges of the label are thereupon moistened 25 on the back. The adhesive material will thus become tacky and the label being laid back down upon the package and pressed thereon will attach itself thereto whether the surface be metal, wood, paper, fiber, or what not. It will be noted that preferably the surface of the envelop which comes 30 in contact with the package bears no adhesive material and that therefore there will be no adhesion between it and the package, although its opposite surface is attached to the back of the label at one or more points as desired. Obviously, since the edges of 35 the label are all securely attached to the package, the envelop, which incloses the bill, invoice, or other matter, will be safely imprisoned beneath it and also that there will be no upturned edges to be torn, no possibility of the envelop or label being used as 40 a handle, no possibility of its being torn away from the package by rough usage of the package in transit or by the presence of other packages near or upon it, and that the envelop with its inclosed invoice, bill or 45 other matter will be preserved intact free from defacement or wrinkling, and finally that access to the envelop may readily be had by simply grasping the envelop as by

the insertion of the point of a knife or equivalent device, and tearing it from the label.

If desired for greater security, the right hand forward under edge of the envelop 70 may be provided with adhesive material, as at 8, which being moistened will attach the envelop to the box at that point. Also if preferred, the adhesive material may be entirely omitted from the back of the label 75 and the label or card attached to the package by tacks, adhesive strips, sewing, or in any other preferred manner.

In Fig. 3 I show a construction in which there is no slit in the label or card, on the contrary, the envelop is set so far to the right that the open end of the envelop will be substantially coincident with the end of the label or card, and the flap of the envelop can therefore be folded over the end 85 in the direction of the arrow and fastened by adhesive material as before.

In Figs. 4 and 5 I show a cheaper construction because instead of there being a completed envelop, a flat and preferably 90 parallel sided piece of paper 9 is folded upon itself, as at 10, the longer part whereof is folded as at 12 at its free end to coincide with the adjacent edge of the label or card to form the flap 5, which will of course 95 be provided with adhesive edges and fold over upon the label in the direction of the arrow.

Obviously the constructions shown in Figs. 3, 4 and 5 may have the adhesive material 8 on the under side of the envelop or folded paper, as stated above in connection with the other figures.

In Figs. 6 and 7 I show a construction specially intended for use on parcel post 105 packages, in which it is necessary that the envelop be opened for inspection by the postal authorities. In this construction I provide in addition to the slit 7 through which the flap 5 of the envelop projects, as 110 in Fig. 1, or in the event that the flap is folded over the edge of the label or card, then immediately adjacent to the edge of the label or card, I make a supplemental slit 15, so that the forward edge of the flap may 115 be inserted in it, yet easily removed therefrom, so that the postal authorities may readily slip the flap backwardly, examine the contents of the envelop, replace the same in the envelop, and again insert the flap within the supplemental slit. Instead of the slit the article may be provided with the usual string and attaching button around which the string is wound, or any other suitable attaching device may be used.

In Figs. 8 and 9 I show a construction in which the label or card is made of material so tough that there is danger that the flap of the envelop might be torn away in the attempt to remove it from beneath the label 130

or card. To facilitate this operation the label or card is provided adjacent to the edges with perforations 16. Instead of the perforations extending entirely through the 5 label or card, scorings, or indentations, as at 17, will in some instances be sufficient.

It will be obvious to those who are familiar with such matters that variations may be made in the details of construction and 10 method of application of the device without departing from the essentials of the invention. For instance, it is not essential that the container should be physically attached to the label or card, although this is the preferred form; also that adhesive material, if used, may be applied in any preferred manner either to the edges of the label or card to be moistened at the time of application to the package, or to the edges of the card and 15 to the entire under side of the container either prior to or at the time of application to the package, or the adhesive material may be applied directly upon the package and the label, card and container pressed thereon. Indeed, the method of attaching the 20 label or card to the package or the container to the label or card, forms no essential part of this invention. Tacks, adhesive strips, sewing, or any other means of attachment may be employed. Also the material of which the label, card or container 25 is made and the shape thereof may all be such as preferred and the label, card or container, one or both, may be waterproofed or 30

strengthened in any preferred manner. I 35 therefore do not limit myself to such details.

I claim:

1. As a new article of manufacture, a label or card and a separate container, adapted to receive and protect a bill, invoice, or other contents, attached to the under side of the label or card, the container having a flap adapted to fold over and be attached to the upper exposed face of the label or card. 40 45

2. As a new article of manufacture, a label or card and a separate container, adapted to receive and protect a bill, invoice or other contents, attached to the under side of the label or card, the container having a flap adapted to fold over and be attached to the upper exposed side of the label or card, and adhesive material on the surface of the container which comes in contact with the package adjacent to the flap. 50 55

3. As a new article of manufacture, a label or card and a separate container, adapted to receive and protect a bill, invoice or other contents, attached to the under side of the label or card, a plurality of the edges of the label or card projecting beyond the container, the container having a flap which extends through a slit in the label or card and is adapted to be folded over and attached to the face of the label or card. 60 65

In testimony whereof I have signed my name to this specification.

WILLIAM M. LAMBERT.
